Application October 10, 1950, Serial No. 12,501

Term of patent 14 years

(Cl. D44—17)

To all whom it may concern:

Be it known that we, Beatrice L. Miller and Gordon Parker, citizens of the United States, residing in Cleveland, county of Cuyahoga, State of Ohio, and Alliance, county of Stark, State of Ohio, respectively, have invented a new, original, and ornamental Design for a Plate or the like, of which the following is a specification, reference being had to the accompanying drawing, forming a part thereof.

The figure is a top plan view of a plate or the like, showing our new design. The shape of the plate or the like is of conventional configuration viewed from the side or bottom thereof.

We claim:

The ornamental design for a plate or the like, substantially as shown and described.

BEATRICE L. MILLER.
GORDON PARKER.
